WELL FLOWING DEVICE

Henry U. Garrett and Clifford M. Peters, Longview, Tex., assignors, by direct and mesne assignments, to Garrett Oil Tools, Inc., Houston, Tex., a corporation of Texas

Application October 3, 1946, Serial No. 700,880

1 Claim. (Cl. 103—228)

1

This invention relates to well flowing devices and more particularly to a new and improved valve mechanism for controlling the flow of fluids from wells through the use of the gas- or air-lift method of producing wells.

In the gas- or air-lift method of producing wells, a bottom hole intermitter valve may be used to permit oil or other fluids to rise to a head above the valve during the heading period until a predetermined condition is reached whereupon applied pressure within the casing may be utilized to blow off the accumulated head after which a succeeding and like cycle may be initiated. In a similar manner a series of flow valves may be spaced along a tubing string and such valves are so adjusted as to operate successively from casing pressure to aerate and blow off successive portions of accumulated liquid head.

Valves of this type are usually loaded to operate within predetermined limits of pressure, and such loading may be effected through the use of spring means or the use of a chamber having a distensible valve actuating element such as a diaphragm bellows or the like. In such devices the loading is predetermined and is fixed when the valve is lowered into the well. If flowing conditions change considerably, as is inevitable during the producing life of a well, it may be necessary to readjust the loading of the valve or valves for operation at pressures different from those for which they were initially set. Such readjustment can be accomplished only by withdrawing the valve or valves from the well.

The present invention is concerned with, and it is one of the objects of the invention, to provide a valve of the type above indicated which may be desirably loaded or charged by controlling the fluid pressure applied within a well to effect flowing of the well through a string of pipe therein.

Another object of the invention is to provide a charged valve in which the maximum differential pressure between the opposite surfaces of the distensible valve actuating element is fixed regardless of the pressure that is exerted to effect flowing of the well.

A still further object is to provide a flow valve in which the valve is charged with a pressure tending to retain the valve closed, the cooperating elements of the valve being so constructed and arranged that the charging pressure may be altered at will without removing the valve from the well.

Still another object is to provide a valve that is of particular utility as an intermitter valve and in which the charging pressure, and hence the operating pressure, may be readily controlled by

2

controlling the fluid pressure admitted to the well in which the valve is used.

The foregoing general statements and objects of the invention, together with other objects and advantages, will be better understood from a consideration of the following description taken in connection with the accompanying drawings in which:

Fig. 1 is an elevational view illustrating one form of the invention as applied to a section of tubing comprising a portion of the flow string in a well;

Fig. 2 is a longitudinal sectional view through a portion of the device showing the volume chamber and valved passages leading to and from such chamber;

Fig. 3 is a sectional view through the valve housing in which a bellows type distensible valve actuator is supplied with pressure fluid from the volume chamber;

Fig. 4 is a vertical sectional view through an alternate form of the invention; and

Fig. 5 is a view showing a plurality of the valves detailed in Fig. 4 in place on a flow string of tubing.

In the embodiment shown in Figs. 1, 2, and 3, the pipe 1 comprising a section of the flow tubing has a surrounding volume skirt 2 of which the upper end is tapered at 3 and is secured to the pipe 1 as by the weld 4. The lower end of the volume skirt is also shown as tapered at 5, and is provided with a plurality of openings 6 for the ingress and egress of fluid to and from the interior of the skirt. It is intended that the skirt 2 shall be of a length to entrap therein sufficient gaseous fluid that liquids will not rise above a predetermined level when the device is submerged in a liquid within a well.

Within the skirt 2 there is a transverse barrier 10 forming an upper annular or volume chamber 11. A pressure differential regulator means exposed to the ambient pressure via openings 6 in skirt 2 and to the pressure interior of chamber 11 is provided to maintain within a predetermined range the differential in pressure between the interior and exterior of chamber 11. Thus, such means can comprise a pressure differential regulator in the form of an inlet check valve 12 and another pressure differential regulator in the form of an outlet check valve 13, wherein the two valves are secured in openings in the barrier 10 and the springs 14 and 15 of these valves are under predetermined compressive stress to hold the balls 16 and 17 upon their respective seats to serve a purpose that will presently appear.

The valve 20 (Figs. 1 and 3) comprises a housing 21 threadedly connected to the lug 22 on the pipe 1 so that the passage 23 at the upper end of the housing may provide for the flow of fluid from the exterior to the interior of the pipe. Such fluid may enter the housing through one or more openings 24 and thence enter the passage 23 whenever the valve 25 moves downwardly from engagement with its seat at the lower end of the passage 23.

The valve stem 26 is secured to a plate 27 which is in turn sealably connected to the upper end of the distensible valve actuating member shown as bellows 28. Inwardly extending lugs or stops 29 in the housing 21 determine the limit of downward movement of the valve 25 during operation of the device.

The lower end of the element 28 is sealed about the upper end of the closure plug 30 at the lower end of the housing 21. This plug is centrally bored and a small pipe or tube 31 is secured therein, the opposite end of this tube being secured to the boss 32 at the upper end of the chamber 11.

In explaining the operation of the device thus far described, it will be assumed that the springs 14 and 15 of the valves 12 and 13 are of such strengths that the balls 16 and 17 are held upon their seats with equal pressures, but it is to be understood that this condition is not a prerequisite to proper operation of the device. When the device is assembled, atmospheric pressure exists both internally and externally of the bellows 28.

If the device is lowered into a column of liquid, such liquid will immediately enter the openings 24 and will exert a pressure upon the bellows 28 that will effect downward movement of the valve 25 whereby such liquid is likewise admitted to the interior of the pipe 1. The interior of the bellows 28 and the chamber 11 remains at atmospheric pressure during initial lowering within the liquid and the valve 25 will continue to move downwardly until it engages the lugs or stops 29 unless in the meantime the pressure below the barrier 10 has risen sufficiently to open the valve 12 and admit fluid under pressure to the chamber 11 and hence to the interior of the distensible member 28. It is obvious therefore that the differential pressure regulator in the form of valve 12 will charge chamber 11 at a pressure less than the maximum value of the ambient pressure by a predetermined amount.

If then, pressure is applied to the surface of the liquid in which the device is immersed, the liquid will rise in the pipe or tubing 1 and flowing is thus initiated. If such flow is to be terminated, the pressure about the flow string 1, and within the casing in which the device is used, is decreased or terminated, whereupon the gaseous fluid trapped within the chamber 11 and the diaphragm 28 acts to close the valve 25 upon its seat. If the applied pressure is greatly reduced or is terminated, the differential pressure regulator in the form of valve 13 acts as a relief valve to release gas in excess of the pressure for which this valve is set. It therefore is apparent that the maximum differential pressure between the interior and the exterior of the extensible member 28 is predetermined and that the differential pressure regulator (valve 13) will release a part of the pressure in chamber 11 when the pressure within the chamber exceeds the ambient pressure by a predetermined amount. Furthermore, subsequent operation of the valve will depend upon the pressure applied exteriorly thereof, and

such pressure is not dependent upon that which was used during a previous operating cycle.

It is to be understood that the valve as above described may be utilized as an intermitter valve for controlling the intermittent admission of well fluids to a flow string, in the manner described, and that conventional differentially loaded flow valves may be used at spaced intervals thereabove to assist in maintaining desired flow from the well during intermitting periods.

On the other hand, the valve may be used as a conventional flow valve. When the valve is used for such purpose, however, the valves 12 and 13 of successive flow valves, will have their closure springs 14 and 15 under such compression that the charging pressure of successive valves will decrease in an orderly manner that automatic opening and closing will occur at such times as to admit air to aerate the column of liquid in the flow string 1 for efficient production of the well. Thus, the charging pressure for the respective flow valves will vary progressively from a relatively low pressure to a relatively high pressure from the lowermost to the uppermost of the valves.

Attention is also directed to the fact that under some circumstances, the volume skirt below the valves 12 and 13 may be omitted.

It is emphasized here that the valves are normally uncharged when they are lowered into the well, but that charging is automatically effected when fluid pressure is applied to the area within the well about the flow string 1. Of course, some initial charge may be provided if so desired. Furthermore, pressure fluid entrapped within the chamber 11, and hence the diaphragm or bellows 28, is released through the valve 13 whenever the surrounding pressure falls a predetermined amount. These features not only assure protection of the distensible member, such as a diaphragm or bellows 28, from excessive differential pressures, but also enables charging the respective valves as desired by mere control of the pressure fluid applied to the well.

An alternate form of the valve of the invention is shown in Fig. 4 wherein like parts are designated by like reference characters. In this embodiment the interior of the bellows 28 comprises a volume chamber 11' and the differential pressure regulators in the form of valves 12' and 13' are located in the plug member 30' to which the lower end of the bellows 28 is sealably attached. A skirt 35 may be attached to the plug 30' and extend downwardly therefrom to serve the same purpose as the skirt 2 shown in the embodiment of Figs. 1, 2, and 3. A strainer barrier 36 within the skirt assures that foreign matter will not be permitted to enter either of the valves 12' and 13', and impair their operation.

It is to be noted that in this embodiment the stop or lugs 29 shown in Fig. 3 have been omitted and that instead there is provided a stud 37 which is attached to the bottom of the plate member 27 so that the downward movement of the valve 25 and associated elements is limited.

In Fig. 5 is shown a string of flow tubing 1 having a plurality of valves 40 spaced along its length. A casing 41 can be provided as well as a conventional well head assembly 42 including a gas inlet pipe 43 and an oil outlet pipe 44. Valves 40 are illustrated in detail in Fig. 4 and their construction and operation described above.

The operation of the alternate embodiment just described is the same as the above described.

mode of operation of the embodiment shown in Figs. 1 to 3 inclusive.

It is to be understood that while the invention is shown and described in connection with the flowing of a well through the tubing therein, the invention also comprehends flowing of a well through the casing in which case the pressure fluid for flowing the well is introduced to the tubing instead of the casing.

Broadly the invention comprehends a well flowing valve mechanism which is so constructed and arranged that the charging pressure thereof may be controlled without removing the valve from the well.

The invention claimed is:

A well flowing device of the class described comprising, a valve housing having a passage therein, a valve in said passage, distensible means operatively connected to said valve to move the valve to and from closed position, a volume chamber communicating with said means, means responsive to ambient pressure for maintaining within a predetermined range the differential in

pressure between the interior and the exterior of the chamber, and a downwardly opening volume skirt having communication with the volume chamber to entrap gaseous fluid therein when the device is lowered into liquid within a well.
